LOADING SYSTEM FOR FORK LIFT TRUCK
 C. Paul Kolthoff, Jr., Naperville, Ill., assignor to International Harvester Company, Chicago, Ill., a corporation of New Jersey

Filed Aug. 22, 1962, Ser. No. 218,739

2 Claims. (Cl. 254—2)

This invention relates in general to material handling apparatus, and more particularly to a new and improved fork lift truck.

In the material handling field it is well known to employ a lift truck having a vertically movable fork secured to the front portion thereof. Such machines have commonly employed relatively complex mechanical or hydraulic systems to effect the raising and lowering of the fork. It has also been conventional practice to provide such machines with intricate electrical systems to control the actuation of the aforementioned mechanical and hydraulic lifting means. As can be readily understood such known devices were not only extremely complicated, but they were also expensive to manufacture and operate. It is, therefore, a principal object of the present invention to provide a fork lift truck which will function effectively to lift pallets and the like, yet which is formed of a relatively simple design which is inexpensive to manufacture and maintain.

Another object of the present invention is to provide a fork lift truck which obviates the necessity of providing a mechanical or hydraulic lifting means and an electrical control circuit therefor.

A further object of the invention is the provision of a lift truck in which the lifting fork is formed integrally with the truck frame, so that the lifting fork is raised and lowered into and out of load carrying position by the movement of the truck frame relative to the ground.

Still another object is to provide a lift truck of the type hereinafter described in which the raising and lowering of the truck frame is accomplished by varying the size of the frame supporting means.

A still further object of the invention is the provision of a lift truck having a lifting fork formed integrally with the frame thereof, and which fork is raised and lowered with respect to the ground by inflating and deflating the ground engaging tires of the vehicle.

Yet another object of the present invention is to provide, in a lift truck of the type hereinafter described, an air supply and control means which is effective to inflate and deflate the supporting tires of the vehicle frame.

Other objects and advantages of the invention will hereinafter become more apparent from an examination of the following description of the annexed drawings which illustrate a preferred embodiment, and wherein:

FIGURE 1 is a side elevational view showing the lift truck in the transport position;

FIGURE 2 is a side elevational view similar to FIGURE 1, but showing the lift truck in the loading position;

FIGURE 3 is a plan view of the apparatus set forth in FIGURE 1 and FIGURE 2 with certain parts broken away for clarity;

FIGURE 4 is a detail view on an enlarged scale, partly in section, of a ground engaging steering wheel of the present invention;

FIGURE 5 is a view partly in section of the control valve of the present invention;

FIGURE 6 is a view taken along the line 6—6 of FIGURE 5; and

FIGURE 7 is a view similar to FIGURE 5 but showing the plunger in a different position.

Referring now to the drawings, wherein like reference characters designate like or corresponding parts throughout the several views, the novel lift truck of the present

invention is indicated in its entirety by reference numeral 10 in FIGURE 1 through FIGURE 3. Truck 10 may be formed of any conventional construction, and in the illustrated embodiment includes a body 11 mounted upon a fore and aft extending frame 12. Lifting fork 13, consisting of spaced-apart prongs 14 and 15, is formed integrally with frame 12, and extends forwardly of body 11. Body 11 is supported by spaced-apart pairs of pneumatic tires 16—17 and 18—19 which are rotatably mounted on frame 12.

The means by which truck 10 is propelled are illustrated schematically in FIGURE 3, and include an engine 20 mounted upon frame 12. A fore and aft extending drive shaft 21 is drivingly associated with front axle 22 by differential means 23, as is well known in the art. The steering of the vehicle is effected by linkage means, not shown, associated with steering wheel 5 and rear wheels 18 and 19.

The air supply means by which tires 16—19 are inflated and deflated are also illustrated schematically in FIGURE 3, and include a compressor 24 of any conventional construction driven by a V-belt 25 or the like. Compressor 24 communicates with an air reservoir 26, which in turn communicates with a circuit pressure regulator 27. It should be understood that while the invention has been illustrated as utilizing a compressor 24 to provide a source of air to reservoir 26, the compressor is not necessary if the reservoir can be recharged periodically from an external source of compressed air, such as, a shop air system. Conduit 28 communicates with regular 27 and conveys air from the reservoir 26 to a three-way valve 30 which meters the air into the front and rear tires, and to a pressure gauge, not shown.

The construction of valve 30 will be best understood from an examination of FIGURE 5 through FIGURE 7. Valve 30 includes a body 31 secured to frame 12 by bolts 32 or the like. A plunger 33 having widened end portions 34 and 35 and a narrowed central stem portion 36 is slidably mounted within bore 37 provided in body 31. Narrowed end portion 34 of plunger 33 is provided with an apertured lug 38 in which the bent end portion of actuating rod 39 is pinned. Actuating rod 39 is secured to handle 40, which in turn is pivotally mounted upon steering column 41.

Valve body 31 is provided with four threaded openings 42—45 which communicate with bore 37. Fittings 46—49 are threadably received within openings 42—45. As can be best understood from FIGURE 5, openings 43—45 are disposed in substantially the same plane, which is spaced apart from opening 42. Conduit 28 is threadably associated with fitting 46, and completes the pneumatic circuit from the air supply source to valve 30. Conduits 50 and 51, which are associated with fittings 47 and 48, lead to the rear and front wheels respectively. Conduit 52 which is associated with fitting 49 leads to a pressure gauge, not shown, which may be any conventional design. With reference to FIGURE 3 it will be noted that T connections 53 and 54 are provided in conduits 50 and 51 to direct the air through conduits 55—58 to the individual tires.

It will be readily understood that as handle 40 is raised, plunger 33 is lowered within bore 37. When handle 40 is raised to a position where enlarged valve portion 35 passes openings 43—45, air will flow into valve 30 from the air supply source through opening 42, and then through openings 43 and 44 to the front and rear wheels. When it is desired to deflate the tires, handle 40 is lowered to a position where enlarged portion 35 passes openings 43—45, thus exposing openings 43—45 to atmospheric pressure, as is shown in FIGURE 7.

The means by which the air is communicated into the individual tires is set forth in detail in FIGURE 4. While

FIGURE 4 illustrates only one steering wheel 18, it should be pointed out that the structure of the other steering wheel 19 is identical, and the structure of driving wheels 16 and 17 is substantially identical, except that wheels 16 and 17 are splined to the front axle.

The rear axle 60 of lift truck 10 is provided with an end portion of reduced diameter 61. Hub 62 is rotatably mounted upon axle 60 by bearings 63, 64 and 65. Axle section 61 is provided with an end portion 66 of further reduced diameter which is threaded to receive bearing retainer 67. Housing 68 surrounds the aforementioned axle structure, and is secured to hub 62 by a plurality of bolts 70, only one of which is shown, which also serves to secure flanges 73 and 74 of tire rim sections 71 and 72 to hub 62. Rim sections 71 and 72 are provided with annular lip portions 75 and 76, which grip the inwardly extending ends of tire 18 in air sealing relation.

Swivel means indicated generally at 78, are provided in the open end portion of housing 68 to accommodate conduit 55. Swivel means 78 include a shaft member 79 having an internally threaded opening for reception of the externally threaded portion of L-shaped fitting 80 which is provided on the end of conduit 55. Fitting 80 is provided with a portion of reduced diameter 81 having a plurality of openings 82 therein, which communicate with radially extending openings 83 formed in shaft portion 79. An annular ring 84 is mounted in the open end of housing 68 and is rotatably mounted upon shaft 79 by bearing 85. Spaced apart shaft seals 86 and 87 are provided between shaft 79 and ring 84, to define an annular chamber 88. A threaded opening 89 extends through the side wall portion of housing 68 and ring 84 and communicates with chamber 88. A conduit section 90 is provided at one end with a threaded fitting 91 which is received in opening 89 and communicates with chamber 88. The other end of conduit section 90 is affixed to nipple 92 which is provided in the tire rim section 71. It can be readily understood that air is conveyed through conduit 55, fitting section 81, and into chamber 88, and from there through conduit section 90 into the interior of tire 18. It should also be apparent that swivel means 78 enables conduit 55 to remain relatively stationary while tire 18 is free to rotate with respect to frame 12.

In operation the operator drives the lift truck in the transport or load carrying position illustrated in FIGURE 1 up to a load L mounted upon a pallet P. He then lowers handle 40, thus raising plunger 33 within valve 30 so as to expose openings 43 and 44 to atmospheric pressure. This allows the air to escape from tires 16-19, and the weight of the vehicle will cause the lift truck to assume the loading position illustrated in

FIGURE 2. The operator then drives the lift truck forward into the position indicated at 10' in FIGURE 2 with the tires in a partially deflated condition. The operator then raises handle 40 causing plunger 33 to move downward within valve 30, thus again exposing openings 43 and 44 to the source of air entering through opening 42. The air is then communicated to tires 16-19 through conduits 55-58 and pallet P is lifted from the ground into a load carrying position. When the lift truck is transported conduits 55-58 remain in a relatively stationary position because of the swivel connection with the various axle housings.

Thus it can be readily understood that what has been provided is a lift truck of relatively simple design, yet which functions effectively without the necessity of complex hydraulic, mechanical, or electrical structure. It should also be understood that the foregoing disclosure relates to only a preferred embodiment of the invention and that numerous modifications or alterations may obviously be made therein without departing from the spirit and the scope of the invention as set forth in the appended claims.

What is claimed is:

1. A mobile fork lift truck comprising, in combination,
  - (a) a frame integrally connected to a load-carrying fork, said fork extending forwardly of said frame,
  - (b) a plurality of inflatable and rotatable tires positioned for movably supporting said frame, said tires having a substantially large radial cross-section,
  - (c) power means disposed on the rearward portion of said frame and connected to said truck in propelling relation,
  - (d) a source of fluid under pressure mounted on said frame,
  - (e) and a control valve with fluid conduit means connected to said source and said tires for controllably inflating and deflating said tires

whereby said fork is raised into a load-carrying position and alternately lowered into load-receiving position respectively.

2. The combination set forth in claim 1 wherein said conduit means includes a fluid swivel passage communicatively connected to each of said tires.
